(57) **CLAIM**

The ornamental design for a silicone massage brush, as shown and described.

DESCRIPTION

FIG. 1 is a perspective view of the silicone massage brush showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view of thereof;

FIG. 8 is a bottom plan view of thereof; and,

FIG. 9 is an enlarged view of portion 9 in FIG. 1.

The dash-dash broken lines shown in the drawings are for the purposes of illustrating portions of the silicone massage brush which form no part of the claimed design. The dash-dot broken lines shown in FIGS. 1 and 9 are for the purposes of showing enlarged areas, and form no part of the claimed design.
